(57) **CLAIM**

The ornamental design for a combination backpack and workstation, as shown and described.

DESCRIPTION

FIG. 1 is a perspective view with the base open and the platforms tucked under flap of a combination backpack and workstation, showing my new design;

FIG. 2 is a side view thereof, with the base open;

FIG. 3 is an opposite side view thereof, with the base open; FIG. 4 is a back view thereof, wherein the broken-away areas on the two straps represent the straps have a longer length than what is shown;

FIG. 5 is a front view thereof, with the base open;

FIG. 6 is a top view thereof, with the base open;

FIG. 7 is a bottom view thereof, with the base open;

FIG. 8 is another perspective view thereof, with the platform tucked; and

FIG. 9 is a top view thereof, with the platforms released; and,

FIG. 10 is a side view thereof, with the base open.

In FIGS. 3, 4, and 6, the broken lines showing as an alternate strap for carrying the combination backpack and workstation are shown for purposes of illustrating the device in a condition of use. These broken lines and the structure they depict form no part of the claimed design.

In FIGS. 1, 3, 6, 8 and 9, and 10 the broken lines showing of environmental structure for purposes of illustrating the combination backpack and workstation in a condition of use. The broken lines and the structure they depict form no part of the claimed design.
